DESIGN FOR A BOTTLE CASING

William J. Behr, Jr., Montclair, N. J.

Application April 3, 1935, Serial No. 56,192

Term of patent 14 years

To all whom it may concern:

Be it known that I, William J. Behr, Jr., a citizen of the United States, residing in Montclair, Essex County, in the State of New Jersey, have invented a certain new, original, and ornamental Design for a Bottle Casing, of which the following is a specification, reference being had to the accompanying drawing, forming a part thereof.

The figure is an elevational view of a bottle casing embodying my new design; the decorative design being repeated at regular intervals around the circumference of the casing.

I claim:

The ornamental design for a bottle casing, as shown and described.

This specification signed this 30th day of March, A. D. 1935.

WILLIAM J. BEHR, JR.
